UNITED STATES PATENT OFFICE

GUSTAV A. WICKERT, JR., OF ELSMERE, NEW YORK

COIN BOX

Application filed April 20, 1928, Serial No. 271,517. Renewed April 19, 1930.

The present invention relates to coin-boxes, or containers for use by bank tellers, or wherever specie has to be handled expeditiously, or payments have to be made, partly at least, in coins of the various current denominations.

The main object of the invention is to supply for the uses indicated a coin box adapted to contain, in a manner convenient of access, the paper-wrapped coin packages of cylindrical shape and of the conventional sizes now commonly used in banks and in the disbursing offices of business houses, said box being provided with gauges or indices which give a visual indication at all times of the total money value of each of the several denominations of coins then in the box. In other words, the object is to supply a coin-box or container, adapted to hold rolls of specie of various denominations, and so constructed that the coins therein are always automatically counted, and the money value thereof is always ascertainable at a glance.

A further object of the invention is to supply a coin-box of such shape and dimensions, and so partitioned into compartments, as to accommodate a maximum amount of the several denominations of coins, and to facilitate the withdrawal of coin packages as desired. This is an important condition to be fulfilled; but it is not easy of fulfillment, because of the different diameters and lengths of the various coin packages or rolls now in use.

The invention further contemplates a box so constructed and arranged that the user can select and remove with the greatest facility the coin-packages desired. In other words, the invention provides an arrangement of the various compartments such that rolls of each of the denominations are always accessible and easily removed from the box.

In order that my said invention and the above-stated and other objects thereof may be clearly understood, I will now describe what is deemed the best embodiment thereof thus far devised, reference being had to the accompanying drawings, wherein—

Fig. 1 is a perspective view of a coin box

constructed according to my invention, the lid of the box being in a raised position;

Fig. 2 is a top plan view of the same;

Figs. 3, 4, 5, 6 and 7 are vertical transverse sections on lines 3—3, 4—4, 5—5, 6—6, and 7—7 (Fig. 2), respectively; showing the arrangement in the several compartments of the box of the coin packages of different denominations.

The box or container is rectangular in shape, and is divided into compartments by vertical partitions B, B', there being, in the box shown in the drawings, two partitions, forming three compartments, C, C¹, C², all of the same height and the same (or approximately the same) length, but of different widths.

The coin rolls D, D' etc. are disposed in horizontal layers, one directly on top of the other. That is to say, two adjacent layers are not staggered with reference the one to the other.

For the purpose of utilizing the cubical contents to the best advantage, the box may have the following dimensions, inside measurements: length 14½ inches; width 8¾ inches; height 6½ inches. The box may with advantage be made of 20-gauge sheet steel.

The cover E, when closed, rests flush upon the top of the box. The lock F is placed near the front edge of the underside of cover E, and its bolt f engages in slot f' near the top of the front wall A' of the box.

The dimensions of the box being as stated above, the vertical partitions B, B' should be so located that compartment C will be 4¾ inches wide; compartment C', 5⅓ inches wide; and compartment C², 3⅓ inches wide.

Compartment C accommodates the packages of halves D (Fig. 4) and quarters D' (Fig. 3). The former (each containing 20 half dollars) are arranged in horizontal parallel rows from front to rear of the box, with one end of each roll abutting against the left hand wall A² of the box. There are five layers of these half-dollar rolls, and in each layer there are seven rolls, making thirty-five rolls of a value of ten dollars each.

The rolls D' of quarters are similarly disposed, and occupy the right hand portion of the same compartment C, the right-hand end of each roll abutting against partition B. 5 Each roll contains 40 quarters, making the value ten dollars; and there are nine packages in each layer, and six layers in all.

The ratio of the respective diameters of the half-dollar rolls and the quarter-dollar rolls is such that the seven rolls D of the former occupy aggregately $\frac{1}{8}$ inch less space horizontally than the nine rolls D' of the latter. To compensate for this slight difference, a metal strip d is introduced to 10 serve as a filler, which strip extends from the top to the bottom of the box at the front thereof (Fig. 2).

The middle compartment C' is designed to accommodate on one side (the left hand side) the rolls D^2 of dimes (Fig. 5) and on the other side the rolls D^3 of nickels (Fig. 6). The former contain fifty dimes each, and there is space in a compartment of the specified dimensions for eight layers of rolls D^2 with twelve rolls in each layer. 20

Rolls D^3 contain forty nickels each, and there is space for seven layers, with ten rolls in each layer.

Again a filler d' is required to occupy $\frac{1}{8}$ 30 of an inch of the length of that part of compartment C' which holds the nickels.

Compartment C² is for the rolls of one cent pieces D⁴ (Fig. 7). Of these there is space in said compartment for eleven rolls 35 in each layer, and for eight layers, there being fifty coins in each roll. The space at the side is occupied by a filler d'' .

Consequently the box as a whole has capacity for 700 half dollars (\$350), 2,160 40 quarters (\$540), 4,800 dimes (\$480), 2,800 nickels (\$140), and 4,400 pennies (\$44); making a total money value of \$1554.

In consequence of the described construction of the box and of the disposition of the 45 various coin packages therein, each package abuts at one of its ends either against one of the side walls (A² or A³) of the box, or against one of the partitions B or B'. Rolls D, for example all abut against 50 wall A², all the rolls D' against the partition B, and so on. Each of the surfaces against which the coin rolls abut has a series of numbers so placed, progressively 55 as to their numerical values and in spaced relation, that the removal of a roll exposes a number, which number will indicate the amount, preferably in money value, of the coins of that particular denomination remaining in the box.

60 This feature of the invention is illustrated in Figs. 3-7. Thus on the surface of wall A², which carries the gauge or index for the half dollar coins, the successive spaces, each corresponding in size to the diameter 65 of a half-dollar, are 10, 20, 30 and so on up

to a maximum of 350 (Fig. 4). This numbering corresponds to the fact that each roll D contains coins of half-dollar denomination to the value of ten dollars. In paying out from the box the coin rolls are 70 always to be taken from the rear of the uppermost layer. Hence the total number of the rolls D in the box at any time will be ten dollars less than the last number exposed on the indicator surface. 75

The ruling of the indicator surfaces by intersecting lines into squares, as shown in the drawings, while convenient is not necessary; the essential thing being that the indicating numerals be so located and be 80 arranged in such order that each one will be hidden by a coin package when the box is filled, and that the correct indication will always be given as the coin rolls are successively removed. 85

According to the system of numbering illustrated in the drawings the covered number next to the one last exposed gives the money value of the coins of that denomination in the box at the time. Hence, 90 the contents being as shown in Figs. 3-7 (incl.) the box would contain \$210 in halves, \$370 in quarters, \$420 in dimes, \$126 in nickels, and \$38.50 in pennies. 95

The box might be, of course, partitioned 95 into as many compartments as there are different denominations of specie. But in the preferred form, which is that illustrated in the drawings, compartments C and C' contain each two series of coin rolls; compartment C being occupied partly by halves and partly by quarters, and compartment C' being occupied partly by dimes and partly by nickels. Therefore the indicator surface for the quarter rolls D' is on the 100 right side thereof, whereas that for the half-dollar rolls D is on the left. Hence the numbering of the squares on the indicator surface for rolls D' must begin at the 105 lower right hand corner, as shown. And the same applies to the indicator surface which serves for the rolls D³ containing nickels, and also to the surface which serves for the pennies. The numbering on the surfaces which serve as indicators for the 110 half dollar rolls D (Fig. 4) and for the dimes D² (Fig. 5) begins at the lower left hand corner. 115

The intersecting lines forming the squares of the several indicators and the numerical figures within said squares, may be made by lithography, or other suitable process, upon thin metal sheets, and the latter may be attached to the box ends and partitions by riveting or by other convenient means; but this is not an essential matter, since said indicators or gauges may obviously be made and secured in position in various ways. 120

It will be seen that when the box is in use, as upon a bank-teller's counter, the 125

several coin rolls all lie horizontally in orderly sequence, and in the most accessible positions, so that there is a maximum of facility for handling; also that when used in the intended manner (the rolls being always taken from the rear of the top layer) the contents of the box are automatically counted at all times.

Coin rolls containing quarters are usually made to contain coins to the value of ten dollars. But sometimes they contain a value of five dollars; and in that case two packages would occupy the space of one of the larger size. So likewise as to packages of pennies, which are sometimes made to contain only twenty-five coins.

Inasmuch as compartment C² has space for only one row of coins, it is preferably made, as shown in Fig. 2, a little wider than the length of the coin roll, so as to provide ample room for the operator's hand.

It is obvious that various modifications in construction and arrangement may be made without departing from the spirit or going beyond the scope of this invention, as defined in the appended claims.

What is claimed:

1. A coin box divided into compartments or coin spaces for holding coin rolls of several denominations, each coin space having an indicator comprising a series of numbers arranged progressively and in spaced relation, each number of the series being hidden from view by one of said rolls when the coin space is occupied.

2. A coin box divided into compartments for containing coin rolls of various denominations of specie currency, each several coin-space being provided with a graduated indicator surface against which the coin rolls of the corresponding denomination abut, and having thereon a series of numbers progressively arranged in such manner that the removal of a coin roll exposes a number which indicates the amount of coin of that denomination left in the box.

3. A coin box divided into compartments by means of vertical partitions providing coin spaces, one for the paper-wrapped coin rolls of each of the current denominations of specie, each space having an indicator surface against which the rolls in that space abut at one end, said surface being subdivided into squares corresponding in number to the maximum number of rolls the space is designed to accommodate, and in size to the diameter of the rolls, each square containing a number, and all being so arranged that the removal of any roll exposes a number on the corresponding indicator surface.

4. A coin box divided by means of vertical partitions into compartments adapted for holding paper wrapped coin rolls of the

several denominations in current use, one dimension of each compartment being approximately a multiple of the diameter of one of such rolls, and the shape being such that the rolls can be arranged in horizontal rows therein, layer upon layer, each coin space being provided with a numerical indicator showing the amount of the coin therein at any time.

5. A coin box divided transversely by vertical partitions into three compartments, one compartment being somewhat wider than the combined lengths of the conventional coin rolls of half dollars and quarters, and having an indicator surface appropriately ruled and numbered on each side, another of said compartments being somewhat wider than the combined lengths of the conventional rolls of dimes and nickels and having also an indicator surface appropriately ruled and numbered on each side, the third compartment being provided with an indicator surface appropriate to the conventional rolls of one-cent pieces.

In testimony whereof I have signed this specification.
